UNITED STATES PATENT OFFICE.

LOUIS H. WELLENSIEK, OF HOUSTON, TEXAS.

ROTARY DRILLING APPARATUS.

Application filed April 15, 1921. Serial No. 461,593.

To all whom it may concern:

Be it known that I, LOUIS H. WELLENSIEK, a citizen of the United States, residing in Houston, county of Harris, and State 5 of Texas, have invented certain new and useful Improvements in Rotary Drilling Apparatus, of which the following is a specification.

This invention relates to certain new and 10 useful improvements in rotary drilling apparatus which is closely related to, and constitutes an improvement of, the type of drilling mechanism shown and described in my application for Patent Serial #417975, 15 filed October 19, 1920.

In the earlier application I have disclosed an apparatus adapted for drilling wells where the formation encountered is shifting and has a tendency to cave in and fill up 20 the bore of the well. The mechanism described in that application includes among other features two concentric strings of pipe and means for rotating the same, the outer pipe or casing being provided to hold back 25 the shifting strata of earth and the inner string or drill stem being provided to drill the hole in advance of the casing both strings of pipe being rotated through the instrumentality of a rotary on the surface of the 30 ground. The present invention represents a modification of the former application in that separate means is provided for rotating each string of pipe and the apparatus is so constructed that joints of pipe may be 35 added to the outer casing while it is in motion thereby avoiding any stoppage of the rotation of that casing while the shifting stratum is being penetrated.

The invention has particular reference to 40 certain novel features of construction and arrangement of parts an example of which is given in this specification and illustrated in the accompanying drawings wherein:

Figure 1 is an elevation of an apparatus 45 constructed in accordance with the invention and constituting an embodiment thereof.

Figure 2 is a plan view taken on the line 2—2 of Figure 1.

Figure 3 is an elevation partially in section drawn to a larger scale than Figure 1 and showing the mechanism attached to the outer casing for rotating and handling same.

Figure 4 is a cross section taken on the line 4—4 of Figure 3.

55 Figure 5 is a detailed elevation showing

the top of an auxiliary derrick and illustrating the rotary for the drill stem.

Figure 6 is an enlarged vertical section of a modified form of hopper from that shown in Figures 1 and 3. 60

Figure 7 is a sectional view of the gripping mechanism for the outer casing.

Figure 8 is an elevation thereof.

Figure 9 is a vertical sectional view of the casing head employed. 65

Figure 10 is a plan view thereof.

Figure 11 is a top view of a clamp which is used when attaching additional joints to the outer casing.

Figure 12 is a side view thereof.

Figure 13 is a vertical sectional view thereof taken on the line 13—13 of Figure 11.

Referring now to the drawings and particularly to Figures 1 and 3 it will be seen that a derrick 20 is provided which may be of the usual form and construction commonly used in drilling wells. An auxiliary derrick 21 is also provided being arranged within the derrick 20 and of less height than the outer derrick. The derrick 21 is preferably 75 constructed of such height that it may conveniently be used in handling a joint of pipe of customary length. In the well bore there is the surface casing 22 which extends to cap rock or to some point above the shifting strata. Within the surface casing is the depth casing 23 which is rotatable and in the operation of the drill is carried down through the shifting strata simultaneously with the movement of the drill bit. The 80 drill stem 24 is positioned within the depth casing 23. 85

The depth casing is rotated by means of a rotary 25 which is mounted on the floor of the derricks and rotated by means of a pinion 26 carried on a shaft 27 upon which is mounted a sprocket wheel 28 to which power may be supplied from any suitable source. The rotary 25 includes a platform 29 which is of such diameter that it will accommodate 95 the men employed in attaching new joints to the depth casing.

The gripping mechanism which is carried by the rotary table 25 in order that the depth casing may be rotated thereby comprises a double grip ring frame 30 which is illustrated in detail in Figures 7 and 8. The frame is preferably constructed of two parts as 30^a and 30^b, the parts being joined together by means of bolts 31. A double set 100 105 110

of grip rings are provided each set consisting of the four rings 32, the rings being arranged in pairs on opposite sides of the casing 23 and adapted to engage therewith. 5 Each pair of rings 32 is mounted on a shaft 33. The shafts are slideable in transverse bearings 34 and the ends of each shaft are secured in the adjusting blocks 35. Adjusting screws 36 the opposite ends of which are 10 threaded in order to engage in threaded holes within the blocks 35 are provided. By rotating the adjusting screws each pair of shafts 33 may be moved transversely so as to move the grip rings 32 to and from engagement with the depth casing 23. It is 15 preferable to have the two sets of grip rings so that as the casing 23 descends one set of rings at a time may be released from engagement with the pipe to allow the pipe collar 20 or coupling to pass through while the other set is in engagement with the pipe. The grip ring frame 30 is attached to the rotary table 29 in any suitable manner; as illustrated, the frame is provided with notches 25 37 adapted to be engaged by lugs on the rotary table.

The depth casing is equipped with a swivel mechanism such as the swivel casing 38 which is preferably cup shaped and is provided with extensions 39 (as shown in Figure 4) by which the swivel may be suspended by means of cables 40 carried on crown blocks 41 positioned at the upper part of the auxiliary derrick 21. In the arrangement illustrated each cable 40 carries a traveling block 42 to which an extension 39 is connected as by means of a turnbuckle 42^a. The turnbuckles enable any adjustment that may be necessary on account of any variations in the length of the suspending cables. 40

The casing 38 forms a housing for the bearing plates 43 and 44 and bearings 45. As shown in the drawing, the bearing plate 43 has a universal movement on the casing 45 37 thus insuring that the swivel will not bind or cramp the casing 38. The form of swivel shown has the further advantage that the pressure on the bearings is equalized thus insuring free rotation of the bearings and 50 preventing excess wear. The casing 38 is held in contact with the swivel members by means of wedge slips 46.

Suitably arranged to receive fluid discharged from the depth casing is a hopper 47. As shown in Figure 3 the hopper has a central opening 48 through which the casing 23 is adapted to pass, the hopper being provided with an internal wall 49 which extends upwardly about the casing 23 for a 55 distance sufficient to give the hopper adequate capacity to accommodate the fluid received from the casing. The upper part of the wall 49 is flared outwardly from the pipe 23. The top joint of the casing is provided with a bell nipple 50 having its edge

sufficiently flared to prevent any substantial amount of fluid from dripping down the pipe 23 and insuring the discharge of same into the hopper. An outlet pipe 51 is provided for discharging the contents of the 70 hopper as may be desired.

In Figure 6 a modified form of hopper is shown. In this type of construction a hopper 47^a is provided with an opening 48^a of such diameter that the couplings of the 75 pipe joints may pass through. A spring pressed collar 52 fits closely about the casing 23. As illustrated, a spring 53 anchored on a stationary lug 54 is guided by a pin 55 and bears against a lug 56 on the collar 52. 80 The tension of the spring 53 tends to press the collar 52 snugly against the casing 23 and whenever a coupling on the pipe 23 comes in contact with this collar it is pushed back against the resiliency of the spring and 85 with the collar 52 thus expanded the pipe coupling may readily pass through the bottom of the hopper.

The drill stem 24 is driven by a rotary 57 which is mounted on the top of the auxiliary 90 derrick. The rotary is operated by any suitable mechanism such as a pinion carried on a shaft 58, the latter shaft being provided with a gear wheel 59 by which power may be transmitted to the shaft by means of the 95 chain belt 60. The belt 60 extends to a sprocket wheel 61 mounted on a shaft 62 to which power is supplied by means of a drive chain carried on the sprocket wheel 63. The shaft 62 also serves to supply power to a 100 drum 64 by means of chain belts 65 and sprocket wheels 66 and 67. The drum carries a cable 68 which extends to a crown block located at the top of the derrick 20, the crown block carrying a cable 69 by 105 which the drill stem 24 is supported. As shown in Figure 1 the drill stem is provided with a swivel 70 of conventional type and a hose 71 for supplying water to the drill stem. The shaft 62 serves to drive a shaft 72 110 by means of a chain drive 73 and sprocket wheels 74 and 75. The shaft 72 carries a drum 76 which is preferably constructed of two equal parts each of which carries a cable 77 which extends to one of the crown 115 blocks 41.

During the operation of the drill water under pressure is forced into the drill stem 24 through the hose 71. At the lower termination of the drill stem is an underreaming bit by which a bore of greater diameter than the drill stem may be constructed thus permitting the rotating casing 23 to be moved downward with the rotation of the drill. The water forced into the drill stem 120 carries away the cuttings from the drilling tool and the resulting mud laden fluid passes up through the annular space between the drill stem 24 and depth casing 23 and is discharged into the hopper 47. 125

It is necessary that provision be made for preventing the fluid from returning to the ground surface on the outside of the depth casing. In other words a tight joint must be made between the surface casing 22 and depth casing 23. In order to provide this tight joint and at the same time permit the couplings which connect the several joints of the depth casing to pass downward with 5 in the surface casing a special type of casing head has been provided which is illustrated in Figures 9 and 10. Fastened to the upper end of the surface casing 22 by means of a coupling 78 there is a tubular head 79 which flares downwardly and which is provided with vertical grooves 80 in its inner wall. Within the head 79 there is a sectional ring formed of the arcuate sections 81 which have peripheral ribs adapted to slide 10 in the grooves 80. This ring is designed to fit closely around the depth casing 23 forming a water tight joint therewith and is formed in sections to make it expansible so that as the casing descends the couplings 15 connecting the joints thereof may pass through. Within the casing 22 there is a ring 82 formed with bearings through which the rods 83 move. The upper ends of the rods are attached to the arcuate sections 81 20 and the lower ends are attached to a movable ring 84. The sliding ring 82 is attached to the stationary ring 84 by means of springs 85. When the pipe coupling strikes against the sections 81 of the ring they are moved 25 downward and the ring is expanded thus allowing the collar to pass through. The springs 85 are thus placed under tension and when the collar has passed they will force the sectional ring 81 back to position 30 thus creating a water tight joint between the depth casing 23 and the surface casing 22.

As drilling progresses the depth casing 23 descends into the bore of the well and from 45 time to time additional joints must be connected to this casing. When it is desired to connect another joint a clamp or grip collar 86 is mounted upon the grip ring casing 30. This collar is illustrated in detail in Figures 50 11, 12, and 13. As shown in the drawings the collar 86 is formed of two sections 86^a and 86^b each section having oppositely arranged outwardly turned ears 87 which are adapted to be clamped together by means of 55 bolts 88 which pass through the ears 87. The bolts are secured by means of grip handles 89. The operative end of each grip handle is bifurcated and a transverse bearing pin 90, anchored in the respective fingers of the handle, passes through a notch in the bolt. The pin 90 is fitted into the notch in the bolt and the handle 89 is depressed. The inner end of the handle is cam shaped and by depressing the same the 60 sections of the grip collar are pulled closely 65

together so that the teeth 91 engage with the casing, the grip collar thereby holding the casing suspended in the bore.

In drilling a well it may be preferable to use drilling apparatus of conventional form 70 until the shifting stratum has been reached. At this point the apparatus described herein is brought into use. The drill stem and the depth casing are rotated and water is forced into the drill stem through the pipe 71, the 75 mud laden fluid containing the borings of the drill returning to the surface through the depth casing and being discharged into the hopper. The under-reaming bit operates to produce a hole of diameter sufficient 80 to allow the depth casing to pass downward simultaneously with the downward movement of the drill.

Whenever it is necessary to add new joints to the drill stem and depth casing the clamp 85 86 is mounted on the grip ring casing 30 and attached to the casing 23 while this casing is in motion. The rotation of the drill stem is stopped and it is elevated so that the top joint or grief stem may be raised above 90 the rotary table 57. After slackening off on the cable 40 to permit the removal of the slips 45 and after removing the nipple 50 the swivel 38 is elevated above the casing 23 and is attached to the drill stem 22 by means 95 of suitable wedge slips, the connection being made at some convenient point below the grief stem. After disconnecting the grief stem and setting it aside a new joint of pipe for the casing 23 is lowered through the upper rotary over the drill stem. Slips are then placed in the upper rotary to attach the drill stem thereto, the cable 40 is slackened and the slips holding the drill stem to the swivel 38 are removed. The swivel is 100 raised to near the upper part of the new joint of casing, the slips 45 inserted, the new joint lowered and attached to the string 105 of casing. The clamp 86 may then be removed. A new joint is added to the drill 110 stem and the latter is lowered into the bore for approximately the distance of one joint of pipe. The grief stem is then connected to the drill stem and drilling resumed. During the entire operation of adding the new 115 joints to the drill stem and depth casing the outer casing is constantly being rotated, although at a reduced speed, if necessary, to accommodate the operators when engaged in work on the platform 29.

The continued movement of the depth casing makes it possible to extend the bore of the well through the shifting strata, the constant rotation of this outer casing serving to prevent the earth from packing 125 against the casing. When the drill and depth casing have passed through the shifting strata the use of the apparatus described herein may be discontinued, if desired, and other drilling apparatus of conventional 130

form may then be employed for the further deepening of the well.

Although the invention has been described herein particularly as applied in drilling through shifting formations it will be recognized by those skilled in the art that the invention is susceptible of serving many other functions. For example, it is specially adapted to drilling through strata characterized by high gas pressure since the rotating casing cases the bore of the well as drilling progresses. The practice of my invention is advantageous whenever it is desirable to case the hole simultaneously with the downward movement of the drill.

Apparatus of preferred form and construction has been illustrated and described for the purpose of showing a way in which this invention may be used, but the inventive thought upon which the application is based, is broader than this illustrative embodiment thereof, and I therefore intend no limitations other than those imposed by the appended claims.

25 What I claim is:—

1. In a well drilling apparatus, two concentric strings of pipe in a well bore and separate means for rotating each string of pipe.
2. In a well drilling apparatus, two concentric strings of pipe in a well bore, separate means for rotating each string of pipe and means for attaching a joint to the outer pipe while same is being rotated.
3. In a well drilling apparatus, a rotary table, a string of pipe arranged to be rotated by said rotary table, a drill stem positioned within said string of pipe and independent means for rotating said drill stem.
4. In a well drilling apparatus, a rotary table, a string of pipe arranged to be rotated thereby, a swivel for said string of pipe, a hopper positioned at the upper end of said string of pipe and adapted to receive fluid discharged therefrom, a drill stem positioned

within said string of pipe and independent means for rotating said drill stem.

5. In a well drilling apparatus, an outer casing, means for rotating same, a drill stem positioned within said outer casing, means for rotating same and a hopper adapted to receive fluid from the outer casing.

6. In a well drilling apparatus, an outer casing, means for rotating same, a drill stem positioned within said outer casing, means for rotating same and a hopper positioned on the swivel of the outer casing.

7. In a well drilling apparatus, an outer casing, means for rotating same, a drill stem positioned within said outer casing, means for rotating same and means for removing the fluid discharged from the outer casing.

8. In a well drilling apparatus, two concentric strings of pipe in a well bore, separate means for rotating each string of pipe, a main derrick, an auxiliary derrick positioned within the main derrick, supporting means for one of the strings of pipe attached to the main derrick, and supporting means for the other string of pipe attached to the auxiliary derrick.

9. In a well drilling apparatus, two concentric strings of pipe adapted for rotation in a well bore, a main derrick, an auxiliary derrick positioned within said main derrick, a rotary for the inner pipe positioned on the auxiliary derrick, a rotary for the outer pipe, adjustable supporting means for the outer pipe attached to auxiliary derrick and adjustable supporting means for the inner pipe attached to the main derrick.

10. In a well drilling apparatus, two concentric strings of pipe in a well bore, separate means for rotating each string of pipe and means for lowering each string of pipe simultaneously.

In witness whereof I have hereunto set my hand and seal this 29th day of March, 1921.

LOUIS H. WELLENSIEK. [L.S.]
